DESIGN FOR A UNIVERSAL PLUMBING
WRENCH

Roy A. Bishop, Atlanta, Ga.

Application August 27, 1940, Serial No. 94,669

Term of patent 3½ years

To all whom it may concern:

Be it known that I, Roy A. Bishop, a citizen of the United States, residing at Atlanta, in the county of De Kalb and State of Georgia, have invented a new, original, and ornamental Design for a Universal Plumbing Wrench, of which the following is a specification, reference being had to the accompanying drawing, forming part thereof.

Figure 1 is an elevational view of a universal plumbing wrench showing my new design.

Figure 2 is an elevational view taken at right angles to Figure 1.

Figure 3 is a plan view showing one end of the wrench, and

Figure 4 is a plan view showing the end of the wrench opposite to that illustrated in Figure 3.

I claim:

The ornamental design for a universal plumbing wrench, as shown.

ROY A. BISHOP.
